PUMPING APPARATUS

Edson F. Gardner, Covington Township, Lackawanna County, Pa.

Application January 25, 1937, Serial No. 122,240

6 Claims. (Cl. 103—44)

This invention appertains to new and useful improvements in pumping apparatus and more particularly to apparatus for pumping fluid from wells.

5 The principal object of the present invention is to provide a pumping apparatus whereby liquid can be pumped from wells without the use of any mechanical parts depending into the well.

Another important object of the invention is 10 to provide a pumping apparatus whereby liquid can be pumped from wells through the action of putting the liquid well column under compression to expand a collection chamber and then subsequently releasing the pressure from the 15 liquid column and allowing displacement of the collected volume.

Another important object of the invention is 20 to distribute the pumping load over both halves of the pumping cycle; i. e., in the one-half of the cycle the power is applied for raising the liquid to the pump, while in the other half of the cycle, the power is applied for raising the liquid above the pump or forcing it into a storage tank under pressure.

25 Other important objects and advantages of the invention will become apparent to the reader of the following specification.

In the drawings:—

30 Figure 1 represents a vertical sectional view through the well casing and well casing head structure and showing in elevation both the pump and well assemblies.

Figure 2 is an end elevational view of the pump.

35 Figure 3 is an enlarged vertical sectional view through the pump.

Figure 4 is a vertical sectional view through the well assembly.

40 Figure 5 is a cross sectional view on the line 5—5 of Figure 4.

Figure 6 is a cross sectional view on the line 6—6 of Figure 4.

Figure 7 is a side elevational view of the movable cylinder.

45 Figure 8 is a cross sectional view on the line 8—8 of Figure 7.

Figure 9 is a top plan view of the cylinder head shown in Figure 2.

Figure 10 is a side elevational view of the cylinder head shown in Figure 9.

Figure 11 is a perspective view of one of the valve elements shown in Figure 4.

Figure 12 is a side elevational view of the piston shell shown in Figure 4 with a part broken away.

Figure 13 is a sectional view on the line 13—13 of Figure 1.

Referring to the drawings wherein like numerals designate like parts, it can be seen that numeral 5 represents the frost-proof well casing 5 head. Numeral 6 generally refers to the pump assembly while numeral 7 generally refers to the internal well assembly.

The well casing head consists of the body 8 having a downwardly tapering bore 9 therein and 10 at its lower portion the circumferential extending groove 10 for receiving the upper end of the well casing 11. The top of the body 8 is provided with the upstanding annular wall 12 receiving the lower portion of the pipe extension 13 which 15 has a cap 14 over its upper end. Numeral 15 represents the hollow core into which the lower end of the threaded stem 16 is threaded. The upper end of the stem 16 being disposed through an opening in the cap 14 and equipped with a 20 nut 17. The port 18 in the body receives one end of the pipe line 19 and this communicates with the interior of the core 15 through a port 20 in the side of the core. A port 8a is formed vertically through the body 8 to provide for 25 drainage and ventilation.

Extending downwardly from the core 15 is the 30 eduction pipe 21 connecting with the well assembly 7.

Referring to Figure 3, it can be seen that 30 the pump 6 consists of the shell 22 having the head 23 at one end secured to the shell by machine screws 24. The opposite end of the shell 22 is internally threaded to receive the externally threaded head 25 and between this and 35 the shell 22 is a packing gland 26 for engagement with the sliding cylinder 27, which cylinder is provided with the head 28 at its inner end and the head 29 at its outer end. The connecting rod 30 for the cylinder 27 extends 40 through the head 29 and threads into the collar 31. A cushion annulus 32 is provided between the head 29 and the collar 31 while a coiled compressible spring 33 is interposed between the collar 31 and the head 28.

45 The head 28 is provided with the hollow superhead structure 33 having the ports 34 in the side thereof. This head 33 is provided with an internally threaded end portion 35 for receiving the clamp ring 36 between which and the head 50 33 a packing gland 37 is clamped and disposed for engagement against the inside of the shell 38 which surrounds the cylinder 27, but terminates in spaced relation at its ends from the heads 23 and 25.

A seating ring 39 is threaded into the clamp ring 38 and has the pin 40 extending inwardly therefrom with the check valve 41 thereon as well as the spring means 42 for normally maintaining the said valve 41 in seated position. The elbow 43 depends from the bottom of the shell 22 and is internally threaded for receiving the adjacent end of the pipe line 19.

Upstanding from the top portion of the shell 22 is the barrel 44 flanged at its upper end as at 10 45 for supporting the flanged end 46 of the bonnet structure 47. A diaphragm 48 is clamped between the flanges 46—45 and traverses the interior of the barrel 44 and bonnet 47 as shown in 15 Figure 3. A cup member 49 rests upon the diaphragm 48 and a coiled compressible spring 50 is interposed between this cup and the top of the bonnet 47. Obviously in place of a diaphragm a piston or some other suitable means can be adopted. A second cup structure 51 bears against the 20 underside of the diaphragm 48 and a coiled compressible spring 52 is interposed between this cup 51 and the valve element 53 which normally engages the removable seat 54. The usual receiving 25 tank (not shown) has a pipe line connection to the neck 55.

In some instances where it may be desirable that the pump shown in Figure 3 be employed for pumping air to the tank, a check valve 56 is 30 mounted on the head 23. When the pump is used for pumping liquid, the air intake 57 is sealed. However, when it is desired that air be compressed, the air intake is opened and operation 35 of the cylinder 27 will cause air to be drawn into the shell 22 and forced into the space 58 and subsequently pass the valve 52 to the tank collecting the same.

Now referring to Figure 4, (the internal well assembly) it can be seen that this assembly consists of the shell 59 internally threaded at its lower end to receive the upper externally threaded portion of the cup-like structure 60 which has the liquid receiving opening 61 in the lower end thereof.

The upper end portion of the shell 59 is internally threaded to receive the externally threaded ring 62 and the enlarged externally threaded lower portion 63 of the bonnet structure 64. A clamp ring 65 is provided on the externally threaded 45 enlarged portion 63. This ring 65 bears against the upper edge of the shell 59 and acts as locking means.

The ring 62 acts as a clamp ring for the packing gland 66 which wipes against the cylinder 67. The ring 62 is also provided with a depending 55 apron 68 spaced from the cylinder 67 and this serves as an abutment for the piston unit generally referred to by numeral 69. This piston unit consists of the shell 70 having the outwardly disposed circumferentially extending flange 71 and the pair of annular members 72—73 thereon. Interposed between the annular member 73 and the member 72 is the packing gland 74 and also a second packing gland 75 is interposed between 60 the flange 71 and the annulus 72. The cylinder 70 of the piston 69 is externally threaded to engage through the annulus 73 and into the internally threaded lower portion of the cylinder 67. A head 76 is threaded into the upper end of the 65 piston cylinder 70 and has opening 77 therein over which the check valve 78 is engageable.

The lower portion of the cylinder 67 adjacent the valve 78 is provided with ports 79. Furthermore, a stem 80 rises from the head 76 and has 70 75 the valve 78 thereon as well as the coiled com-

pressible spring 81 for normally urging the valve 78 against the head 76 and over the opening 77.

The upper end of the cylinder 67 is provided with the head 82 having openings 83 therein normally closed by the valve 84. A stem 85 rises from the head 82 and has the valve 84 thereon and normally urged downwardly against the head 82 and over the openings 83 by the spring 86.

As can be seen in Figure 4, a strong compressible coiled spring 87 is interposed between the 10 flanged lower end of the piston 69 and the bottom of the cup-like section 60.

It can now be seen, that when the cylinder 27 of the pump 6 in Figure 3 is moved toward the right the column of fluid in the pipe 19—21 is 15 placed under pressure and this forces the cylinder 67 and piston 69 downwardly in the shell 59 against the tension of the spring 87. As this assembly moves downwardly, the valve 78 will open and allow liquid to fill the cylinder 67 as well as 20 the increased space 88 between the shell 59 and the cylinder 67. The cylinder 27 is now moved toward the left in Figure 3 which releases the pressure on the column of fluid, permitting the spring 87 to exert its tension which drives the piston 69 upwardly displacing the liquid from the space 88 into the cylinder 67 through ports 79 and in view of the fact that it cannot leave the cylinder 67 by way of the valve 78, it must pass upwardly through the ports 83. This fluid is then 30 in the shell 22 in advance of the superhead 33 of the cylinder 27. By now reversing the direction of the cylinder 27 so that the cylinder 27 is moving toward the right, the trapped liquid is put under compression so that the valve 41 opens 35 and allows a portion of the liquid to pass into the superhead 33 and out through the ports 34 to the space 58. Due to the pressure above the valve 53, this liquid cannot at this time pass valve 53. The remaining portion of the liquid is forced 40 into shell 59 as heretofore described. The next movement toward the left by the piston 27 will drive the fluid from the space 58 pass the valve 53 to the pipe line from the neck 55 (not shown).

The diaphragm 48 and springs 50—52 serve 45 as a differential assembly in conjunction with the valve 53. The same serving to maintain a sufficient and practically constant pressure on the valve 53 regardless of the hydraulic pressure 50 in neck 55 so that when the cylinder 27 is moved toward the right all of the pressure generated thereby will be communicated to the cylinder assembly denoted by reference character 7.

It can now be seen that the spring 33 interposed between the shoulder 31 and the head 28 provides a novel means of taking up the shock of temporary excessive pressure and restoring this energy when the shock period has passed. Under normal operating pressures there is no movement of connecting rod 30 through the head 29, but when an abnormal pressure such as a water hammer is encountered against the head 28, the plunger 27 is forced outwardly along the connecting rod 30 against the spring 33. When the excess pressure is removed, the spring 33 returns plunger 27 to its normal position.

It is preferable that the valve seats 39 and 54 each have a small bleeder slot therein to provide for priming of pipes 19 and 21.

While the foregoing specification sets forth the 70 invention in specific terms, it is to be understood that numerous changes in the shape, size and materials may be resorted to without departing from the spirit and scope of the invention as claimed hereinafter.

Having described the invention, what is claimed as new is:—

1. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, a pipe leading to the pump, a union between the upper end of the eduction pipe and the last mentioned pipe, said union consisting of a body adapted to be disposed over the top of the usual well casing, a downwardly tapering pocket in the said body, a hollow core disposed into the pocket, said body and core having registering ports with which the pipe from the pump can communicate, and means for urging the core snugly into the said pocket of the body.
2. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, a pipe leading to the pump, a union between the upper end of the eduction pipe and the last-mentioned pipe, said union consisting of a body adapted to be disposed over the top of the usual well casing, a downwardly tapering pocket in the said body, a hollow core disposed into the pocket, said body and core having registering ports with which the pipe from the pump can communicate, and means for urging the core snugly into the said pocket of the body, and a bonnet structure for the body and a threaded stem extending upwardly from the core and through the upper portion of the bonnet structure and provided with a nut at its upper end adapted to be fed downwardly on the stem and against the upper end of the bonnet.
3. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, said pump comprising a shell having a head at each end thereof, a longitudinally slidable cylinder in the shell, said shell being provided with a port therein for communication with the eduction pipe, a head structure on the slidable cylinder, a check valve provided for passing liquid from the liquid intake end of the shell to the liquid discharge end of the shell, and packing means on the head structure, said packing means adapted to wipe the inside of the shell, an outwardly movable check valve at the outlet port of the shell and differential spring means for maintaining the said last-mentioned check valve in closed position when pressure is being applied by the pump to the column of liquid in the eduction pipe.
4. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, said pump comprising a shell having a head at each end thereof, a longitudinally slidable cylinder in the shell, said shell being provided with a port therein for communication with the eduction pipe, a head structure on the slidable cylinder, a check valve provided for passing liquid from the liquid intake end of the shell to the liquid discharge end of the shell, and packing means on the head structure, said packing means adapted to wipe the inside of the shell.
5. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, said pump comprising a shell having a head at each end thereof, a longitudinally slidable cylinder in the shell, said shell being provided with a port therein for communication with the eduction pipe, a head structure on the slidable cylinder, a check valve provided for passing liquid from the liquid intake end of the shell to the liquid discharge end of the shell, and packing means on the head structure, said packing means adapted to wipe the inside of the shell, said cylinder being provided with an actuating rod, and shock absorbing means between the rod and the cylinder.
6. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, said pump comprising a shell having a head at each end thereof, a longitudinally slidable cylinder in the shell, said shell being provided with a port therein for communication with the eduction pipe, a head structure on the slidable cylinder, a check valve provided for passing liquid from the liquid intake end of the shell to the liquid discharge end of the shell, an outlet port for the shell, and packing means on the head structure, said packing means adapted to wipe the inside of the shell, an outwardly movable check valve at the outlet port of the shell and differential spring means for maintaining the said last-mentioned check valve in closed position when pressure is being applied by the pump to the column of liquid in the eduction pipe.
7. In combination, a pump, a well liquid eduction pipe, a connection between the pump and the upper portion of the eduction pipe, and means at the lower end of the eduction pipe responsive to pressure on the liquid column in the eduction pipe by the pump for trapping and lifting liquid through the eduction pipe, said pump comprising a shell having communication with the eduction pipe, a check valve provided for passing liquid from the liquid intake end of the shell to the liquid discharge end of the shell, an outlet port for the shell, and packing means on the head structure, said packing means adapted to wipe the inside of the shell, an outwardly movable check valve at the outlet port of the shell, and differential spring means for maintaining the said last-mentioned check valve in closed position, said differential spring means consisting of a spring imposed upon said valve, a second spring acting upon the first spring, the pressure exerted by the second spring on the first spring being varied by hydraulic pressure applied to the second spring.

EDSON F. GARDNER.
